SYNCHRONOUS GEARED MOTOR HOUSING

Ted N. Svarnias, Elmwood Park, Ill., assignor to International Register Company, Chicago, Ill., a corporation of Illinois

Filed Aug. 23, 1965, Ser. No. 86,668

Term of patent 14 years

(Cl. D26—5)

FIG. 1 is a front elevational view of a synchronous geared motor housing, showing my new design;

FIG. 2 is a left side elevational view, the right side being substantially a mirror image thereof;

FIG. 3 is a rear elevational view;

FIG. 4 is a bottom plan view; and

FIG. 5 is a top plan view thereof.

I claim:

The ornamental design for a synchronous geared motor housing, substantially as shown and described.
